UNITED STATES PATENT OFFICE.

FREDRICH OLSEN, OF DOVER, NEW JERSEY.

DETONATING OR DISRUPTIVE EXPLOSIVE.

No Drawing.

Application filed April 16, 1921. Serial No. 462,000.

To all whom it may concern:

Be it known that I, FREDRICH OLSEN, a subject of the King of Great Britain, and a resident of Dover, county of Morris, and 55
5 State of New Jersey, have invented an Improvement in Detonating or Disruptive Explosives, of which the following is a specification.

The subject of this invention is a detonating or disruptive explosive.

The main object of the invention is the production of a disruptive explosive from nitrocellulose smokeless powder or cordite.

Another object of the invention is the 15 production of a non-freezing explosive composition which will be useful either in underground places such as mines or tunnels, or in open places such as quarries or excavations, or in other places in which explosives may be used.

My composition consists of a mixture of a propellant powder, such as is found in the forms known as nitrocellulose smokeless powder or cordite, with either ammonium perchlorate or with nitro-hydrocarbons such as trinitrotoluene or both, and with or without the ordinary so-called "dope ingredients" of dynamite or blasting powders, such as combustible non-explosive carbonaceous materials (e. g., wood meal, flour), 30 inorganic nitrates (e. g., saltpetre) or manganese dioxide.

It is well known that nitrocellulose has long been used in the manufacture of explosives, and attempts have been made to use nitrocellulose with nitroglycerine and the ordinary ingredients of dynamites and blasting powders, but the lack of success which usually attends the use of these products has resulted from their insensitivity. It has been my experience that when nitrocellulose is used in amounts more than say 5% of the weight of the nitroglycerine, or other liquid nitric acid ester of aliphatic 40 alcohols, mixtures are obtained which have a very slight ability to propagate the wave of detonation, especially if the mixture has been stored for a few months.

I have found that the dense form of col- 50 loided nitrocellulose found in smokeless powder or cordite, even when ground, be-

haves quite differently from the loose and fluffy collodion cotton or gun cotton. The former is less hygroscopic and receives the initial detonating impulse from the blasting 55 cap. The hard colloided particles transmit the wave of detonation in a manner which is not possible in the case of the fibrous collodion cotton or gun cotton.

Further, the action of colloided nitrocel- 60 lulose in the form of smokeless powder or cordite can not be confused with that of the nitrocellulose used in gelatinizing nitroglycerine or nitrocellulose. Inasmuch as the latter nitrocellulose is present in amounts 65 of about 3% of the weight of the nitroglycerine or in less amounts when used with liquid nitrotoluenes and forms a stiff gelatinous mass, whereas colloided nitrocellulose must be used in amounts which are 200 70 or 300% as great as the amounts of uncolloided nitrocellulose employed. This may be due in part to the changes which have been brought about by the colloidizing process to which the nitrocellulose has been sub- 75 jected in mixing it with solvents and converting it into smokeless powder.

It is believed that the enormous pressures to which the nitrocellulose is subjected in the colloidizing process actually changes the 80 molecular structures of the nitrocellulose. It is certain that all the physical properties of nitrocellulose have been altered by the colloidizing action and the evidences for changes in chemical structure are based on 85 experiments in which great differences in viscosity of solutions of uncolloided and colloided nitrocellulose were observed. That mechanical processes do actually promote changes in the mechanical structure of ni- 90 trocellulose has been proven by dividing a batch of unpurified nitrated cellulose into two parts each of which was given the regular purification process with the exception that one part was subjected to an additional 95 ten hours of beating treatment. This extra beating actually produced a chemical change in some of the nitrocellulose giving the material the properties of nitrated hydrocellulose, and greatly changing the viscosity 100 of solutions.

The change in gelatinizing properties is

also due to the fact that a very specially prepared nitrocellulose is employed in the manufacture of gelatine dynamites. This nitrocellulose has usually a nitrogen content of 11.9-12.15%, is 100% soluble in a mixture of two parts ether and one part alcohol, and gives stiff jellies with nitro-glycerine when used in the proportion of about 3%. Great care is exercised in either 10 eliminating or at least reducing to a minimum all boiling treatments, especially with diluted alkali solutions, in the manufacture of this collodion cotton. Experiments have shown that the treatment accorded to pyro-cotton during the purification process is of such a severe nature that when applied to collodion cotton practically ruins the colloid properties of this substance. A great number of tests show that the viscosity of normally prepared collodion cotton in a certain apparatus was measured at 3,600 as against 5 to 15 for the same material which had been subjected to the regular pyrocotton purification treatment.

25 I have discovered that, if instead of nitro-glycerine, ammonium perchlorate or nitro-hydrocarbon such as nitrotoluene are used as the explosive base, explosive mixtures having very desirable properties are obtained.

30 The essential features of the explosive composition herein described is that it affords an outlet for surplus or waste propellant powders, the utilization or disposal of which, presents a formidable problem.

35 For example, not only does the use of ammonium perchlorate assure a complete detonation of the propellant powder with the use of an ordinary No. 6 detonator, and an excellent propagation of the explosive 40 wave, but also serves as an oxygen carrier for the propellant powder, thereby procuring a greater strength and freedom from obnoxious elements.

Many grades of powder can be obtained 45 by varying the proportions of ammonium perchlorate and propellant powders. For example, grades can readily be made to correspond to the 20, 30, 40%, etc., nitro-glycerine dynamites or ammonium nitrate 50 powders. The following mixtures may serve as examples of powders which can be made.

	Per cents.									
Trinitrotoluene	85 to 25									
Propellant powder	15 to 75									
or	55									
Ammonium perchlorate	20	40	40	30	20	20	20	20	10	50
Trinitrotoluene	30									50
Propellant powders	40	15	50	30	50	50	20	20	40	40
Wood meal	5		10			3	5			
Paraffin wax	30	10	30			17	10	10		
Ground vegetable ivory	10						5		5	
Nitre					30	30	20		10	10
Manganese dioxide					30	30	20	25		

A greater cohesiveness may be secured by the use of mixtures of trinitrotoluene and dinitrotoluene, liquid trinitrotoluene, various liquid or semi-liquid nitrohydrocarbons or other common binding agents, such as castor oil, shellac compounds, etc. The use of these substances does not, however, vary the nature of my invention, and I claim my invention with or without their use.

The most suitable results are obtained when the smokeless powder or cordite is ground so that 100% will pass through a standard 30 mesh sieve, and at least 50% will pass through a 50 mesh sieve. But I do not wish to limit my invention by the suggested use of this granulated form, or by the suggested pulverization which I have indicated. My invention covers the use of the said material with or without this pulverization. It may be found desirable to use some other perchlorate than ammonium perchlorate, as for example, potassium perchlorate. My invention covers the use of any available inorganic perchlorate.

Having described my invention what I claim as new and desire to secure by Letters Patent, is:—

1. The herein described explosive, containing ammonium perchlorate, trinitrotoluene, a propellant powder and a combustible non-explosive material.
2. The herein described explosive, containing ammonium perchlorate, trinitrotoluene and a propellant powder.
3. The herein described explosive, containing trinitrotoluene and a propellant powder.
4. The herein described explosive, containing 30% of ammonium perchlorate, 30% of trinitrotoluene and 40% of propellant powder.

FREDRICH OLSEN.
